UNITED STATES PATENT OFFICE.

WILLIAM McCRAVE, OF PITTSTON, ASSIGNOR OF ONE-HALF OF HIS RIGHT
TO JOHN A. PRICE, OF SCRANTON, PENNSYLVANIA.

STOVE-GRAVE.

SPECIFICATION forming part of Letters Patent No. 225,623, dated March 16, 1880.

Application filed October 16, 1879.

To all whom it may concern:

Be it known that I, WILLIAM McCRAVE, of Pittston, in the county of Lackawanna and State of Pennsylvania, have invented a certain 5 new and Improved Stove-Grate; and I do hereby declare the following to be a full, clear, and exact description of the same, reference being had to the accompanying drawings, forming part of this specification, in which—

10 Figure 1 is a top-plan view, showing the grate in position for use; Fig. 2, a plan view of the middle plate; Fig. 3, a plan view of the lower plate, and Fig. 4 a cross-section in line $\alpha\alpha$, Fig. 1.

15 Similar letters of reference in the several figures denote the same parts.

The object of this invention is to improve the construction and organization of stove-grates, so as to secure to as great an extent as 20 possible the capacity to sift the ashes from the live coals without danger of dumping the coals into the ash-pan, and without obstructing the access of air to support combustion.

To this end my improved grate introduces a 25 new principle—namely, the combination of three grate surfaces or plates, in which the holes of the upper plate are arranged substantially over the bars or coal-supporting surfaces of the lower plate, while the middle plate serves 30 as a cut-off to prevent the coals from falling through the holes of the upper plate, and also serves to scrape off and discharge into the ash-pan such ashes or other substances as do pass through said holes or spaces and lodge on the 35 lower plates.

The grates may be of any size and shape, according to the character of the furnace, stove, or other structure wherein they are to be used.

40 In the above drawings I have shown a circular grate oscillating around its center; but the same three-plate principle may be applied to longitudinally or laterally shaking or sliding grates, the essential principle being that 45 the lower plate shall present bars or coal-supports under the spaces of the upper plate, and that the middle plate shall operate to clear the space between the two other plates.

In the drawings, A indicates the upper 50 plate, B the lower plate, and C the middle plate.

The upper plate is provided with a circular rim, a , from which lugs d extend down and serve to support the lower plate, the latter being provided with arms f , which are connected 55 to the lugs by pins E or any other suitable fastening. The rim a is beveled downward and outward on its outer upper edge. The upper plate is further provided with a central hub, A' , which projects downward below 60 the plane of the plate, forming a journal or bearing which centers the middle plate, C. The upper part of the hub is of greater diameter than the lower part, and extends above the plane of the plate A in the form of a truncated cone, having lateral wings or flanges a' . An orifice extends down vertically through 65 the center of the hub, through which a portion of the air is supplied to support combustion. Radial supporting-surfaces A^2 extend 70 from the hub to the rim, and are provided with suitable openings a^2 . Each of the surfaces A^2 has one of its upper corners or edges beveled or inclined downward, as shown at a^3 , and the opposite lower edge or corner beveled or 75 inclined in the same direction, as shown at a^4 , for purposes which will be hereinafter explained. The supporting-surfaces A^2 are about equal in extent to the open spaces between them, and are of the same general form. 80 The flanges a' extend from the inner end of said supporting-surfaces toward or to the top of the hub A' .

The lower plate, B, is provided with a central hub, B' , from which supporting-surfaces 85 B^2 extend outward to the periphery of the middle plate, C, and are each furnished with a lug, f , for purpose of support, as above described. Each of the surfaces B^2 is suitably 90 perforated, as shown at b . The surfaces B^2 are arranged directly under the spaces which exist between the supporting-surfaces A^2 of the upper plate, so that any coals, clinkers, or other materials than fine coal-ash, that may fall through between the supporting-surfaces 95 of the upper plate will lodge upon the surfaces B^2 of the lower plate.

The upper and lower plates are arranged at such a distance apart as to receive and accommodate between them the middle plate, C, 100 which is provided with a hub, C' , supporting-surfaces C^2 , and a rim, C^3 , from which project

four (more or less) arms, C⁴. The surfaces C² are provided with suitable perforations e.

All the openings or passages through the plates A B C, or any of them, are made smaller 5 at the top than at the bottom, or, in other words, expand downward, so as to afford a more perfect clearance for the ashes, coals, and cinders; and at the outer extremity of the beveled edges a⁴ the inner wall of the rim a is 10 cut away or recessed, as shown at a⁵, for the same purpose.

An arm or lug, a⁶, extends from the rim a, to receive the poker or other iron used in shaking the grate.

15 The entire structure thus organized is supported upon the projecting arms C⁴ of the middle plate, which are dropped into suitable recesses in the wall of the stove or any part thereof which is designed to support the grate. 20 The middle plate is thus held rigidly in place, while the upper and lower plates, connected firmly together by means of the lugs d, arms f, and pins e, are capable of being vibrated laterally upon the plate C. The extent of this 25 vibration is limited by suitable stops a⁷, or other means, so that the supporting-surfaces C² can be brought directly under the large open spaces of the plate A or under the supporting-surfaces A² of said plate.

30 The operation of the grate is as follows: In its normal condition the surfaces C² are directly under the spaces A³, thus furnishing a support for the fuel throughout the entire extent of the grate, with suitable openings for 35 the upward passage of air to support combustion.

When it is desired to shake the grate the latter is turned as far as the stops will permit, thus opening the spaces A³ and allowing the 40 ashes and cinders to fall through upon the surfaces B², when, by reversing the movement of the grate, the lateral wall of the part C² sweeps the ashes and cinders from the surfaces B² and discharges them into the ash-pan beneath.

45 It will be observed that on their under side the surfaces C² are provided at one edge with a downwardly-projecting flange, c⁷, extending down to the surface B², so as to effectually 50 sweep the latter. When the upper spaces, A³, are open this downwardly-projecting flange c⁷ comes under the beveled edge a³. This beveled or inclined edge serves to properly 55 deflect the ashes and cinders toward that side of the surfaces B² from which they are to be discharged into the ash-pan, while the beveled lower corner, a⁴, furnishes clearance for the cinders as they are thus discharged.

The arrangement of all these parts is such 60 as to present at all times a supporting-surface to the mass of fuel above, but with abundant openings at all times for the upward passage of air.

65 By the vibration of the grate a series of pockets or cups are alternately opened at their

upper end to receive the ashes and cinders from above, and are then opened at one side for the discharge of their contents into the ash-pan beneath, and the device which serves to sweep their contents out at the side thus 70 opened by the act of sweeping closes and cuts off the entrance of cinders from above until the discharge of the pockets has been accomplished and they have been again opened. The flanges a' serve to strengthen the upper 75 plate, and also operate as agitators to cause the proper separation of the ashes and cinders from the live coals during the shaking of the grate.

What I claim, and desire to secure by Letters Patent, is—

1. A horizontal flat grate consisting of the upper part, A, provided with openings intermediate between the coal-supporting surfaces, the lower part, B, provided with openings beneath the coal-supporting surfaces of the part A and supporting-surfaces beneath the openings of the part A, and an intermediate part, C, provided with arms or scrapers, which operate to scrape the ashes from the supporting-surfaces of the lower part, B, into the ash-pan below, substantially as described. 90

2. In a horizontal flat grate, the combination of the parts A B, rigidly connected to each other, and part C, interposed between 95 them, the parts A B and the part C being movable with relation to each other, substantially in the manner and for the purpose specified.

3. In a horizontal flat grate, the combination of a stationary central or middle grate-section with upper and lower sections, vibrating upon a center, and having the surfaces of the lower section under the openings of the upper section, whereby the vibration of the 105 upper and lower sections together alternately opens and closes a series of pockets, which receive the falling ashes and cinders, and discharges the ashes and cinders therefrom into the ash-box below, substantially as described. 110

4. In combination with the horizontal flat grate, the upper plate, A, having the central hub, A', extending above the plane of the plate and provided with flanges a' around its central opening, and, further, having perforated supporting-surfaces A² extending from the hub to the rim a, with beveled edges a³ a⁴, and with dumping openings or spaces A³ alternating with the surfaces A², substantially as 115 described.

5. The combination of the three-part grate with raised center, central opening, perforated middle and lower sections, double series of pockets, central guide, and attachments and connections, for the purpose specified. 120
